Elwood Harvey Allent INVENTOR

UNITED STATES PATENT OFFICE.

ELWOOD HARVEY ALLCUTT, OF KANSAS CITY, MISSOURI.

SWITCH.

SPECIFICATION forming part of Letters Patent No. 311,461, dated February 3, 1885.

Application filed December 2, 1884. (No model.)

To all whom it may concern:

Be it known that I, ELWOOD HARVEY ALLCUTT, a citizen of the United States, residing at Kansas City, in the county of Jackson and State of Missouri, have invented a new and useful Switch, of which the following is a specification.

My invention relates to switches used in connection with a system of rails, upon each of which, in turn, operates a wheel attached to a carrier, and to which carrier is attached and suspended below the system of rails the thing or load to be carried.

The object of my invention is threefold, as follows, to wit: first, to obtain such a switch-hanger that the ends of the stationary rails, upon which, in the first instance, moves the carrier to which is attached the weight or thing to be carried, can be easily set in their proper position and held there rigidly and without possibility of spreading. The second object is to obtain an arrangement or device for swinging on the side of the switch-hanger opposite to that by which the stationary rails approach a movable rail pivoted at one end to the right or left, so that its free end can be made to coincide in turn with the end of each of the stationary rails and then firmly and rigidly held, thus forming a continuation of the track afforded by any of the said stationary rails from the point where said stationary rail is firmly attached to the switch-hanger. The third object is to obtain an arrangement or device to prevent any possibility of a carrier from leaving any of the said stationary rails, except when end of each of said stationary rails coincides in turn with the free end of the movable rail, as spoken of above under the second object, and also to prevent a carrier from leaving the said movable rail in the direction of the said stationary rails, except when the ends of said stationary rails coincide in turn with the free end of the said movable rail swung into such coincidence, and there secured, as stated in object two above. I accomplish these objects by the mechanism illustrated in the accompanying drawings, in which—

Figure 1 is a front vertical view of the switch-hanger. Fig. 2 is a top horizontal view of the switch-hanger. Fig. 3 is a right-hand vertical view of the switch-hanger. Fig. 4 is

a horizontal sectional view of the switch-hanger, as indicated by the dotted line *xx* in Fig. 1. Fig. 5 is a top horizontal view of a complete switch, and showing also the stationary rails and the movable rail. Fig. 6 represents a vertical sectional view from front of Fig. 5, cut through by plane *yy*, as shown in Fig. 5, showing also a carrier and its wheel 60 in position on one of the rails when the free end of the movable rail is brought into coincidence with end of one of the stationary rails.

Similar letters refer to similar parts throughout the several views. 65

I accomplish the first object above enumerated by the switch-hanger shown in Figs. 1, 2, 3, and 4, Plate 1. To accomplish this object I make the switch-hanger to consist of a plate, A, as shown in Figs. 1, 2, 3, 5, and 6, and two or more legs, *b b b*, as shown in Figs. 1 and 6, each leg being supplied with a foot, *e e f*, as shown in Fig. 4, a portion, *e*, of which foot is also shown in Figs. 1, 2, 3, 5, and 6. The foot projects toward the left (see *e*, Fig. 4) from the bottom of each leg *b*, so that such projecting portion of each foot may act as a support for the end of one of the rails *g g g*, as shown in Figs. 5 and 6, which said rails *g g g*, approaching from behind the switch-hanger, as shown in Fig. 5, are carried each one over said projecting portion of each foot, as above, and flush with the front of the bottom of the legs *b b b*—that is to say, at *z z z* in Fig. 4. These rails *g g g*, supported by said projections *e e e* 85 in Fig. 4, are each bolted, riveted, or otherwise rigidly secured to the enlargement of the lower end of the legs *b b b*, just above the feet *e c f e c f e c f*, the arrangement being shown in Fig. 6. The plate A, Fig. 1, the legs *b b b*, Fig. 1, and the feet *e c c*, Fig. 1, together constitute the switch-hanger. These may be all cast or constructed in one piece, or the plate A, Fig. 1, the legs *b b b*, Fig. 1, and the feet *e c f e c f e c f*, Fig. 4, may be each cast or constructed separately and firmly fastened together in their proper position by riveting or bolting to insure rigidity and prevent the ends of the rails *g g g* from approaching toward or moving away from one another. 90 95 100

I accomplish my second object by constructing the system of levers *m k i* and the casting *l* as shown in Figs. 5 and 6. The bar *k* is bent, as shown in Fig. 6, and pivoted at one end to

the bar *m*, as shown in Fig. 6. The bar *m*, Fig. 6, is pivoted through a slot at point *n*, as shown in Fig. 6, a slight up-and-down motion of the bar *m* being permitted by said slot at *n*. The 5 end *t* of the bent bar *k* (see Fig. 6) projects through right-hand end of bar *i*, fitting in a hole through bar *i* so loosely as to permit a slight up-and-down motion at the other end of the bent bar *k*. The left-hand end of the bar *i*, as 10 shown in Fig. 6, is turned up at a right angle and bolted or otherwise firmly secured to the side of the free end of the movable rail *h*, Figs. 5 and 6. The bar *i* rests on the projection *c c c* of the feet, (shown in Figs. 4 and 6,) and is held firmly against these feet by the projection *D* of the right-hand leg *b*, as shown in Figs. 5 and 6. In the under edge of the left arm of bent bar *k*, as shown in Fig. 6, are cut a series of 15 notches, *v v v*, in number equal to the number of stationary rails *g g g*, (see Fig. 5,) and distant from each other a space equal to the distance between the ends of stationary rails *g g g*, where said ends of stationary rails *g g g* are attached to the enlargements of the legs of 20 the hanger. These notches are of a size sufficient to permit them to fit easily over the bottom of a slot in casting *l*, through which slot in casting *l* the bar *k* passes, as shown in Fig. 6. To swing free end of the movable 25 rail *h*, so as to make it coincide with the end of the stationary rails *g g g*, lift the bar *m*, so as to release any notch *v* in bar *k* from bottom of said slot in casting *l*. The bar *k* can then be swung easily to the right or left, as 30 desired, thus moving bar *i* and the free end of movable rail *h* toward the right or left until said free end of the movable rail *h* coincides with the end of one of the other stationary rails *g g g*, when another notch, *v*, in bar *k*, 35 coming over the bottom of the said slot in casting *l*, allows bar *k* to drop slightly, holding the free end of the movable rail *h* firmly secured in coincidence with the end of said last-mentioned stationary rail *g*.

40 I accomplish my third object by means of the projections *f f f* of the feet, as shown in Fig. 4, together with the plate *i* (shown in Figs. 5 and 6) and that portion of the bent bar *k* to the left of the band *s s*', as shown in Fig. 6.

45 When the carrier *o* and wheel *w* are upon the movable rail *h*, as shown in Fig. 6, they are prevented from leaving said movable rail *h*, Figs. 5 and 6, if the free end of said movable rail *h* is slightly to the left of its proper position, (that is, the position where the free end of movable rail *h* coincides with the end of one of the stationary rails *g g g*,) by the lower part of carrier *o* striking against the foot *c* of the leg *b* immediately to the left, all as shown in 50 Fig. 6. If the free end of said movable rail *h* is slightly to the right of its said proper position, the upper part of carrier *o* will, by striking against leg *b* next on right to carrier *o*, pre-

vent the wheel *w* and carrier *o*, Fig. 6, from leaving the movable rail *h*. The legs *b b b*, 65 Fig. 6, are curved away from the rails *g g g*, so that they do not strike the carrier *o* while said carrier is moving along rails *g g g*. The end *t* of bar *k* projects through bar *i*, as shown at *t* in Fig. 6, fitting loosely, so as to permit a slight up-and-down motion at the other end of bent bar *k*. When the bent bar *k*, Fig. 6, is swung to the left, thus swinging *i* and the movable rail *h* to the left, said projection of bent bar *k* at *t*, Fig. 6, will, by striking against the foot 70 *c* of right-hand leg *b*, prevent the free end of the movable rail *h* from swinging to the left of the left-hand stationary rail *g*, as shown in Fig. 6; also, when bent bar *k* and bar *i* and free end of movable rail *h* are swung to the right, the 75 upturned left-hand end of bar *i*, as shown in Figs. 5 and 6, will, by striking against the projection *d* in Figs. 1, 2, 3, 4, 5, and 6, of right-hand leg *b*, prevent free end of the movable rail *h* from being swung to the right of the 80 end of the right-hand stationary rail *g*, all as shown in Figs. 5 and 6. When the wheel *w* and carrier *o* are approaching toward and from behind the switch-hanger on any of the stationary rails *g g g*, if the movable rail *h*, Fig. 6, were moved slightly to the right, the bar *k* would also move to the right, and the lower right-angled corner of the bent bar *k*, as shown by *s*' in Fig. 6, would prevent wheel *w* and carrier *o* from leaving the said stationary rail *g*, 85 Fig. 6, and if the movable rail *h* were moved slightly to the left of its proper position the wheel *w* would be prevented from leaving said rail *g* by the carrier *o* striking against the free end of movable rail *h* or the bar *i*, all as 90 shown in Figs. 5 and 6.

I claim as my invention—

1. A switch-hanger for holding in place rigidly two or more stationary rails, so as to prevent the said rails from spreading apart, 105 approaching one another, or from rising or falling from position, said switch-hanger being composed of a top plate, *A*, and two or more legs, *b b b*, each leg supplied with a foot, *c c c*, all substantially as set forth.

2. A device for preventing a carrier from leaving the system of rails at the switch, said device obtained by combination of the bars *k* and *i*, the feet *c c c*, and the legs *b b b*, all substantially as set forth.

3. A device obtained by combination of the levers *m*, *k*, and *i* and the casting *l*, for swinging a movable rail pivoted at one end, and holding the free end of said movable rail firmly in coincidence with the end of any stationary rail attached to the switch-hanger, all substantially as set forth.

ELWOOD HARVEY ALLCUTT.
